UNITED STATES PATENT OFFICE.

JOHN CLIFFORD WHITRIDGE, OF COLUMBUS, OHIO, ASSIGNOR TO THE BUCKEYE STEEL
CASTINGS COMPANY, OF COLUMBUS, OHIO.

CAR-COUPLING DEVICE.

Application filed November 23, 1923, Serial No. 676,577.

To all whom it may concern:

Be it known that I, JOHN C. WHITRIDGE, a citizen of the United States, and resident of Columbus, in the county of Franklin and 5 State of Ohio, have invented certain new and useful Improvements in Car-Coupling Devices; and I do hereby declare the following to be a full, clear, and exact description of the invention, such as will enable 10 others skilled in the art to which it appertains to make and use the same.

This invention relates to car coupling devices and has special reference to devices for connecting the European hook type of 15 coupler with the automatic Master Car Builders' type of coupler. There are in use many cars which are equipped with hook type of couplers which must frequently be coupled to cars equipped with the M. C. B. 20 automatic couplers, and the present invention provides an efficient device for use in such cases. The invention provides a device which may be readily assembled or disassembled but which can not be easily lost, 25 which will readily accommodate itself to the buffering position of the cars, and which will be out of the way when two cars equipped with M. C. B. couplings are to be coupled.

30 The invention is illustrated in the accompanying drawing in which Figure 1 is a plan view of the improved device as it appears in use; Figure 2 is a side elevation of the same; Figure 3 is a side elevation 35 showing the device folded to accommodate the buffering position of the cars.

In the drawing, the reference numeral 1 designates the M. C. B. coupler head having the usual knuckle 2, and 3 denotes the hook 40 type coupler. In the practice of the present invention, the M. C. B. coupler head is provided on its opposite sides with lateral headed studs 4, the axes of which are in alignment. Upon these studs are engaged 45 the links 5 which project forwardly beyond the coupler head, in the normal positions of the parts, and are engaged with headed studs 6 on the ends of a cross bar 7 which has an elongated eye or loop 8 projecting 50 forwardly from its front side, at its center to be engaged with the hook 3, as shown. The end portions of the slots 9 in the link 5 are of such diameter that they may engage the shanks of the studs 4 but cannot 55 pass over the heads thereof, so that said

heads retain the links upon the studs. Midway their ends, however, the links are expanded, as at 10, to a width which will permit them to clear the heads of the studs, and the studs are so located that the expanded middle portions of the links will lie in the transverse vertical plane of the knuckle 2. Consequently, movement of the bar 7 toward the coupler head 1 a distance less than one-half the length of the links 60 will bring said bar into contact with the knuckle 2, and the knuckle must, therefore, be removed to permit the parts to be assembled or disassembled. Loss or theft of 65 parts is thus avoided.

To assemble the parts, the knuckle 2 is removed, the links are engaged over the studs 6 on the bar 7, and then brought back and engaged over the studs 4 on the coupler head 1. The knuckle 2 is then placed in 70 position whereupon the device will be ready for use. A reverse operation, of course, 75 will disassemble the parts.

When in the coupled position shown in 80 Figures 1 and 2, if the cars should come together from any cause, the links and the bar 7 with the eye 8 may fold downwardly, as in Figure 3, so that breakage or other damage to the parts cannot occur. Moreover, the device may hang suspended from 85 the studs on the coupler head so that it will be out of the way when both cars to be coupled are equipped with M. C. B. coupler heads.

Having fully described my invention 90 what I claim as new and desire to secure by Letters-Patent, is:-

1. In a device of the character set forth, the combination with a coupler head, of slotted links engaged with the sides of said head, and slideable longitudinally of the head and a cross bar disposed between the links in front of the coupler head and having its ends engaged in the slots of the links, and slideable therein longitudinally of the links to be released therefrom, the cross bar being provided between its ends with an elongated eye to engage a hook coupler. 100

2. In a device of the character set forth, the combination with a coupler head having a knuckle, of slotted links mounted on the sides of the coupler head, a cross bar slideably mounted in said links and provided with means for engagement with a hook coupler, said links having their centers nor- 105 110

5 mally in the transverse vertical plane of the knuckle and having their slots widened at their centers to permit release of the cross bar after removal of the knuckle from the

10 3. In a device of the character set forth, the combination with a coupler head having headed studs on its sides, of links engaged with said studs and laterally expanded midway their ends whereby to clear the heads of the studs, a cross bar between the outer ends of the links, headed studs on the ends 15 of the cross bar engaged in the links, and means normally preventing disengagement

15 4. In a device of the character set forth, the combination of a coupler head provided with headed studs at respective sides and

20 having a knuckle, of a cross bar provided with means for engagement of a hook coupler and having headed studs at its ends, and slotted links connecting the studs of the coupler head with the studs of the cross bar and having central enlarged portions, 25 said slotted links being so proportioned relatively to the coupler head and cross bar that the devices cannot be applied to or removed from the coupling head without removing the knuckle of the latter.

25 In testimony whereof, I have signed this 30 specification in the presence of two subscribing witnesses.

JOHN CLIFFORD WHITRIDGE.
